UNITED STATES PATENT OFFICE.

JOE J. SCHULTZ, OF WINDSOR, NORTH DAKOTA.

RAZOR-BLADE HOLDER.

Application filed May 6, 1922. Serial No. 558,886.

To all whom it may concern:

Be it known that I, JOE J. SCHULTZ, a citizen of the United States, residing at Windsor, in the county of Stutsman and State of

5 North Dakota, have invented certain new and useful Improvements in Razor-Blade Holders, of which the following is a specification, reference being had to the accompanying drawings.

10 This invention relates to improvements in razor blade holders, and more particularly to a device for holding razor blades while sharpening the same.

An important object of the invention is 15 to provide a device of this character which may be either separately constructed or constructed upon the tang of a razor blade or of a razor blade holder constructed in imitation of the usual straight style of razor.

20 A further object of the invention is to provide a device of this character to which a blade may be readily applied and by which the blade when applied is held firmly in position.

25 A still further object of the invention is to provide a device of this character which may be very cheaply and readily constructed.

These and other objects I accomplish by 30 the construction and arrangement shown in the accompanying drawings wherein for the purpose of illustration is shown a preferred embodiment of my invention and wherein like reference characters designate like parts throughout.

35 In the drawings:

Figure 1 is a side elevation showing a blade holding shank constructed in accordance with my invention and provided with a handle;

40 Figure 2 is an edge elevation thereof partially in section; and

Figure 3 is a view similar to that shown in Figure 1, the shank comprising the tail or finger receiving portion of a razor blade 45 or blade holder.

Referring now more particularly to the drawings, the numeral 10 indicates a handle portion, which may, as hereinbefore stated, be formed either of a separate piece of material or by the blade portion of a razor or the blade holding portion of a safety razor constructed in imitation of the ordinary razor construction, the first and last constructions being herein shown. Where an 55 ordinary handle is employed, it is provided with a reduced blade holding extension 11

forming at the end of the handle a shoulder 12 provided with an undercut slot 13 flush with the upper surface of the blade holding extension 11, the purpose of which will hereinafter appear.

At the end of the blade holding extension 11 an offset 14 is provided at one side of the blade corresponding to the thickness of a safety razor blade 15, the extension being of 65 a width equal to the internal slot 16 formed in certain types of safety razor blades. The upper end of the offset 14 is provided with an enlarged head 17 of greater width than the slot 16 of the blade to be employed. The 70 combined thicknesses of the extension 11, offset 14 and head 17 are less than the width of the slot 16 so that by turning the blade transversely of the slot the same may be applied over the head. By then arranging the 75 blade longitudinally of the extension 11 the blade may have its end moved downwardly into engagement with the upper surface of the extension 11 and aligned with the slot 13 so that it may enter therein. As is well 80 known to those familiar with the art, the slots 16 of this type of razor blades terminate short of the ends thereof and accordingly a comparatively broad, flat surface is formed which bears against the upper surface of the 85 arm. This bearing, when the blade is in fully applied position and engaged in the undercut slot, effectually prevents downward movement of the outer end of the blade since the metal between the end of the slot and 90 the end of the blade will bear against the upper surface, and the end of the blade is effectually prevented from elevation by the overhanging shoulder formed by the slot. Movement in the opposite direction will, of 95 course, be prevented by the head 17 and transverse movement of the blade will be prevented by the engagement of the offset 14 against the side walls of the slot 16.

When it is desired to form a blade holding device in accordance with my invention upon the shank of a razor or blade holder constructed in resemblance of a razor, the terminal portion 18, which is adapted to be engaged by the fingers while shaving, is 105 formed to provide the structure hereinbefore set forth, as indicated in Figure 3.

From the foregoing it is believed to be obvious that a blade holder constructed in accordance with my invention is particularly well adapted for the purpose for which it is intended by reason of the fact that the 110

blade may be readily applied to and removed therefrom and will be very firmly held when applied. It will furthermore be obvious that the construction as hereinbefore set forth and illustrated is capable of some change and modification without materially departing from the spirit of my invention and I accordingly do not limit myself thereto except as hereinafter claimed.

10 I claim:—

1. The combination with a longitudinally internally slotted razor blade, of a member having a shank provided with an extension, said extension being of a width substantially equal to the slot of the blade and provided at one side thereof with a head of greater width than the extension, and a slot formed in the shank of the member and adapted to receive the end of a blade 15 engaging said extension and having the head thereof extending through the slot.

2. The combination with a razor blade having an internal longitudinal slot, the ends of which are spaced from the ends of 25 the blade, of a member having a shank provided with an extension of a width substantially equal to the slot of the blade and provided at one side thereof with a head of greater width than the slot of said blade, 30 and a slot formed in the shank of the member and adapted to receive the end of a blade engaging such extension and having the head thereof extending through said

slot, said head being spaced from the adjacent end of the slot of the shank a distance 35 slightly greater than the distance between the ends of the slot and the ends of the blade.

3. The combination with an internally longitudinally slotted razor blade, of a member 40 having a shank provided with an extension, said extension being of a width equal to the width of the blade and provided at one side thereof with a relatively wide head offset from the extension a distance approximately equal to the thickness of the blade, said member having a slot 45 formed in the shank thereof opening toward said head and adapted for the reception of the end of the blade when engaged with said extension and having the head of the extension extended through the slot thereof.

4. A razor blade holder for blades having an internal longitudinal slot comprising a shank having an extension against which a portion of the body of the blade is adapted 55 to rest, the extremity of the extension being provided with a relatively wide head adapted for extension through the slot, and the shank being provided with an overhanging portion disposed at the same side of the extension as the head and adapted to overlie 60 the end of the blade.

In testimony whereof I hereunto affix my signature.

JOE J. SCHULTZ.
